UNITED STATES PATENT OFFICE.

LEWIS N. HÉNAULT, OF ALBANY, NEW YORK.

DECK-SASH SUPPORT.

Specification of Letters Patent. Patented Jan. 27, 1920.

1,328,874.

Application filed December 17, 1917. Serial No. 207,545.

To all whom it may concern:

Be it known that I, LEWIS N. HÉNAULT, a citizen of the United States, residing at Albany, county of Albany, State of New York, have invented certain new and useful Improvements in Deck - Sash Supports, of which the following is a specification.

This invention relates to deck sash supports, and has more particular reference to an improved hinge, by means of which sashes may be mounted in the deck frames or jambs of cars and the like.

The object is to provide a deck sash holder of a construction which admits of the ready removal and positioning of the sashes in the deck frame; which admits of the adjustment of the sash into various angles for the purposes of ventilation; and which yieldingly retains the sashes in adjusted position.

Another important object of this invention is the provision of a deck sash holder which is so constructed as to readily release the sash and admit of the removal thereof through either side of the deck frame, and thus prevent injury to the screening or other fixtures supported by or arranged closely adjacent to the deck.

The above and various other objects and advantages of this invention will be in part described and in part understood from the following detailed description of the present preferred embodiment, the same being illustrated in the accompanying drawing, wherein:

Figure 1 is an outer side elevation of a deck sash support constructed according to the present invention.

Fig. 2 is an outer end elevation of the same.

Fig. 3 is a horizontal section taken longitudinally through the device.

Fig. 4 is a transverse section taken through the device intermediate the ends thereof, certain parts being removed and parts being shown in dotted lines and in various adjusted positions.

Fig. 5 is a similar section looking in the direction opposite from that of Fig. 4.

Referring to the drawing, there is disclosed but a single support although it is to be understood that the supports are to be used in pairs, one arranged upon each end of the deck sash and secured to the adjacent portion of the deck frame or jambs.

In the present disclosure the device comprises a body part or bracket made up of

an attaching plate 10 of triangular or other suitable shape provided with openings 11' near two of its corners adapted to receive attaching screws or the like for securing plate 10 to the frame or jamb of the deck. The apex or third corner of the plate 10 is provided with a bearing opening 11 of substantial size. The plate 10 is provided intermediate its ends with a pair of spaced apart bars 12 connected at their outer ends by cross-piece 13 which is preferably detachably mounted on the bars 12 by means of lugs 14 and screws 15. The lugs 14 project inwardly from the cross-piece 13 and are adapted to lie against the inner opposite faces of the bars 12. The bracket is also provided with an intermediate plate 16 forming a brace and which is recessed at opposite edges to receive the bars 12 therein, the plate 16 being arranged mid-way between the opposite ends of the bars.

The bracket is provided with a longitudinally shiftable bearing and latch-bolt 17 which is slidably mounted in the cross-piece 13 and the brace 16, the cross-piece and the plate conforming substantially to the contour of the base-plate 10, and the bolt 17 being mounted in the outer ends of the same in axial alinement with the bearing opening 11 of the base-plate. The end of the bolt adjacent the base-plate 10 is provided with a relatively large journal portion 18 adapted to fit in the opening 11 and support a disk 19 thereon arranged against the inner side of the plate 10. The disk 19, as shown in detail in Fig. 5 is provided preferably with a flat side adapted to bear against the plate 10 and is provided on its opposite side with a segmental corrugated portion 20 presenting radial corrugations and extending substantially one-third over the surface of the disk. The disk 19 is also provided with a laterally extending flange 21 adapted to bear against the frame on the deck side and having screw openings therein to receive screws or the like for securing the flange 21 to the deck side. The flange 21 is preferably located at the marginal edge of the disk 19 adjacent the corrugations 20 to dispose the latter at the outer side of the vertical plane of the axis of the disk.

The bolt 17 is provided, near the journal 18 thereof, with an integral or otherwise suitably and fixedly mounted disk 22 conforming in contour and size to the disk 19. The disk 22 is provided upon one face with

radial corrugations 23 extending throughout substantially one-third of the surface of the disk, and being arranged to engage with the corrugations 20 of the disk 19 to hold the latter in various positions of adjustment. The bolt 17 is provided with a helical spring 24 arranged between the cross-piece 13 and a transverse pin 25 secured through the bolt 17. The pin 25 is adapted to normally bear 10 against the brace 16 when the spring 20 is fully expanded, and when the disks 19 and 22 are in interlocked relation. The spring 24 tensions the disks together and yieldingly holds the disk 19 from turning. The corrugations are provided with rounded surfaces 15 adapted to admit of the yielding of the corrugations past one another when the disk 19 is forced about the journal 18 for adjusting the deck sash in various degrees of inclination, such as shown in dotted lines in Figs. 2, 4 and 5.

The cross-piece 13 is provided with an outstanding lug 26 upon its inner end to which is pivoted a lever 27. One end of the lever 27 is forked and provided with a longitudinal slot 28, and is adapted to receive between the fork arms the flattened extremity 29 of the bolt 17. A pin 30 is secured transversely through the slot 28 and the extremity 29 to connect the lever to the bolt. The lever 27 is preferably arched inwardly toward the cross-piece 13 intermediate its ends to space the connected end of the lever from the bracket, and the other end of the lever 35 is adapted to be swung upon its pivotal connection with the lug 26 into the position shown in dotted lines in Fig. 3 for retracting the bolt 17 and withdrawing the journal 18 from the opening 11. When the bolt is 40 retracted the disks are separated, and the disk 19 may be readily withdrawn from the bracket. The free end of the lever 27 is spaced from the deck sash, and extends in a direction away from the same so that when 45 a tool is employed for swinging the lever 27, and should the tool slip there is no

danger of injuring the deck sash. Furthermore, this location of the lever 27 admits free access thereto and admits the ready application of a tool, or the hand to the lever. 50 The disk 19 may of course be withdrawn from the bracket through the top, the bottom, or the outer side thereof, and the deck sash may thus be removed from its jamb through either the inner or outer side of the 55 deck frame.

It is of course understood that various changes and modifications may be made in the details of construction of the above specifically described embodiment of this 60 invention without departing from the spirit thereof, such changes and modifications being restricted only by the scope of the following claim.

I claim:

In a deck sash support, the combination of a bracket including a pair of spaced parallel cross plates having aligned openings, a bolt 65 slidably engaging in said openings and provided with an enlarged journaled portion 70 on one end adapted to enter the opening in one of said plates, a spring coiled about said bolt and connected thereto and arranged within the bracket for urging said journal into said opening, a locking member formed 75 integrally with the bolt near the journaled end thereof, a second locking member rotatably mounted on said journaled end and adapted to be clamped between one of said bracket plates and said first named locking 80 lever for returning the rotatable locking lever in various adjusted positions about the journal, a bracket formed upon the bracket plate remote from the bracket plate engaged by said journaled ends, a lever pivotally 85 mounted upon said bracket and having one end bifurcated and slotted, a pin extending through said slot and through said bolt for connecting the lever and bolt to shift the bolt longitudinally upon shiftable movement of the lever.

LEWIS N. HÉNAULT.
